UNITED STATES PATENT OFFICE.

JAMES FRANK GRANT, OF BALTIMORE, MARYLAND.

DESIGN FOR A BADGE OR SIMILAR ARTICLE.

SPECIFICATION forming part of Design No. 32,633, dated May 8, 1900:

Application filed March 21, 1900. Serial No. 9,617. Term of patent 14 years.

To all whom it may concern:

Be it known that I, JAMES FRANK GRANT, a citizen of the United States, residing at Baltimore, in the State of Maryland, have invented and produced a new and original Design for Badges or Similar Articles, of which the following is a specification, reference being had to the accompanying drawings, forming a part thereof.

Figure 1 is a front view of a badge, showing my new design; and Fig. 2, a central vertical section of the same.

As shown in the drawings, the leading or material feature of my design consists of a shield divided into two parts by a horizontal line, the upper or smaller part of which is

plain and slightly depressed, as plainly shown in Fig. 2, and the lower or larger part is ornamented with a single star resting between the horns of a crescent, with lines radiating from the star in all directions, as shown in Fig. 1.

Having thus fully described my invention, what I claim as new, and desire to secure by Letters Patent, is—

The design for a badge or similar article, substantially as herein shown and described.

J. FRANK GRANT. [L. S.]
